BICYCLE LIGHT

Viktor Schreckengost, 2265 Stillman Road,
Cleveland Heights 18, Ohio

Original design application June 15, 1964, Ser. No. 80,397, now Patent No. 203,064, dated Nov. 3, 1965. Divided and this application Aug. 6, 1965, Ser. No. 87,046

Term of patent 14 years

(Cl. D48—24)

The fragmentary portion of the bicycle shown in broken lines in FIGURE 1 is included for illustrative purposes only.

This application is a division of my copending application, Serial No. D-80,397, filed June 15, 1964, now Patent Des. 203,064.

I claim:

The ornamental design for a bicycle light, substantially as shown and described.
